UNITED STATES PATENT OFFICE

ANDERS N. F. MOHR, OF STEWART, MINNESOTA

RAILROAD LOCK SWITCH

Application filed January 31, 1931. Serial No. 512,637.

This invention relates to new and useful improvements in rail-road lock switches, and has for its object to provide a switching system that will work automatically and 5 may be relied upon under all circumstances.

It is thus thought that the said device will not only contribute to the safety of the rail-road service generally, but will also, as an automatically working unit, be of great importance as a labor saving medium, in addition to assuring faster train service.

As the construction of this device is comparatively simple, the cost of manufacturing should be proportionately low.

With the above and other objects in view, this invention consists of the novel features of construction, combination and arrangements of parts, hereinafter fully described, claimed and illustrated in the accompanying drawings forming part of this specification, and in which similar characters of reference indicate corresponding parts in all views, and in which:

Figure 1 is a top plan view of parts of a rail-road track and of a vehicle, with which my improved switch mechanism is connected.

Figure 2, being taken on the line 2—2 of Figure 1, is a rear elevational view.

Figure 3 is a vertical sectional view taken on the line 3—3 of Figure 1; and

Figure 4 is a vertical section taken on the line 4—4 of Figure 1.

Referring more particularly to the drawings, the numerals 10 and 11 represent the rails of a track in which a pair of switches 12, 13 are arranged to direct a vehicle, such as a locomotive 14, to another course or track having a rail 15, this latter rail being 40 a continuation of the rail 11, while the switch 12, as shown in full lines, is a continuation of the other rail of the second mentioned track. The switch 13 is a continuation of the other rail of the first mentioned track.

These switches, limitedly movable about points at their junction with the respective rails from which they continue, are attached by a tie member 16, in the present instance 50 of metal, and on this member is a block or

post 17, at the switch 13. Attached to the post at one of its ends is a rod 18 which, having a hinge joint 19, is movable at its opposite end in a slot of a guide block 20. This latter end is hooked to accommodate 55 the slot, where antifriction means may also be provided.

On the opposite end of the member 16 is another block or post 21, to which is attached a jointed rod 22, and one terminal of this latter rod is movable in a slot provided in a block 23. The blocks 20 and 23 are seated on a metal sheet 25, preferably of iron, and on this sheet are also positioned the usual ties, each numbered 24. The 65 structure also includes another metal sheet 26, which is bolted to the top of the ties 24, as at 27. This latter sheet, which has therein recesses 28, 29 for the posts 17, 21, and which covers the rods 18, 22, provides a support for the points of the switches. 70

The locomotive has a fender 30, and below this is located a guide block 31. In mating relation with this guide is a movable shoe 32, which is held in an uppermost position 75 by a spring 33. The spring is attached to the fender at one end, and at its other end finds a bearing in an elongated recess of the shoe, so that the latter is slidable longitudinally; but as the top part of the shoe, as seen in Figure 2, is extended upwardly, while a part 34 of the frame of the fender lies below the extension, it follows that the shoe, on sliding movement thereof, as seen in broken lines of the said figure, is pressed 80 downwardly below its mating guide. 85

In order to operate the shoe, which is a switch actuator, as shall hereinafter appear, a link 35, slidably supported, as at 36, on the structure of the vehicle 14, is movable 90 on operation of a pivot lever 37, the top terminal of which is suitably located in the vehicle. The link 35 is provided at one end with a pin, which is movable vertically in an aperture in one end 38 of the shoe, during 95 upward and downward movement of the latter.

The lever 37 includes an extension or arm 39, which is positioned between stops 40 and 41 of the link 35, so that on operation of 100

said lever the shoe 32 is slideable, and the length of the sliding movement may be determined by the height of the stop 41. Contractile and compressible springs 42 and 43 are provided below the respective blocks 17, 21, and these springs find terminal anchorages on angle plates, which are attached below the blocks and below the rails of the structure, as clearly shown in Figure 4.

- 10 The switches are set, as shown in Figure 1, for movement of the vehicle over the track, which includes the rail 15, but in order to change the switches for moving the machine over the rail to track which 15 includes the rail 10 and switch 13, the lever 37 is operated to lower the shoe 32, whereon the said shoe contacts with the post 17 to move the switches into positions shown in broken lines.
- 20 No waiting time may be consumed for this operation, and no signalling apparatus or personnel may be required; the line or track being selected by the engineer or driver of the vehicle, according to prearrangement.

25 The actuator or shoe may be arranged before leaving a station or commencing a journey, for operating any number of switches, without manipulation by the engineer.

30 Another guide block and shoe shown at 31 and 32, may be arranged opposite the post or block 21, and any lever, not shown, may be used adjacent the track for again 35 moving the switches after passage thereover of a locomotive or vehicle equipped with the actuator of my improved switch controlling mechanism. A block or guide 31, being used in place of a movable shoe 32, may be 40 utilized to operate a switch post.

45 It is obvious that changes may be made in the form, construction and arrangement of the several parts, as shown, within the scope of the appended claims, without departing from the spirit of the invention, and I do not, therefore, limit myself to the construction and arrangement shown and described herein.

50 What I claim as new, and desire to secure by Letters Patent of the United States, is:

1. The combination with a vehicle track having a switch, means disposed below the switch and movable with said switch, of a post carried by the said means, and a switch 55 actuator adapted to be carried on a vehicle for contacting with the post to move the switch for changing the course of a vehicle during its travel.

2. The combination with a pair of vehicle 60 tracks, and a vehicle, said tracks having a pair of switches, which latter have a tie member, of a post carried on said member, guide means disposed adjacent said member, a rod mounted at one of its ends on said 65 post and slidably movable at its opposite

end on said means for guiding the switches during their movement, and switch actuating mechanism, said mechanism having a shoe mounted on the vehicle for contacting with the post to move the switches for changing the path of the vehicle during its travel from one track to the other.

3. In combination with a pair of vehicle tracks, and a vehicle, said tracks having a pair of switches, which latter have a tie member, a post carried on said member, guide means disposed adjacent said member, a relatively movable rod including a hinge, said rod having one of its ends rigid with said post and having its opposite end slidably mounted on said first means whereby to yieldably guide the switches during their movement, and switch actuating mechanism, said mechanism having a shoe mounted on the vehicle for contacting with the post to move the switches for changing the path of the vehicle during its travel from one track to the other.

Signed at Hutchinson in the county of McLeod and State of Minnesota this 7th day of January, A. D. 1931.
